US00D344723S

United States Patent [19]

Tonozuka et al.

[11] Patent Number: Des. 344,723

[45] Date of Patent: ** Mar. 1, 1994

[54] **MAGNETIC TAPE STORAGE UNIT FOR AN ELECTRONIC COMPUTER**

D. 319,637 9/1991 Kusel et al. D14/108

[75] Inventors: **Kazutoshi Tonozuka, Tokyo; Masahiro Honda, Yamagata; Kimio Nobeashi, Tokyo, all of Japan**

OTHER PUBLICATIONS

NEC Brochure on a magnetic tape storage unit for an electronic computer, Model Nos. N7641, N7642, published Dec. 1987.

[73] Assignee: **NEC Corporation, Tokyo, Japan**

Primary Examiner—Wallace R. Burke

[**] Term: **14 Years**

Assistant Examiner—Freda S. Nunn

[21] Appl. No.: **879,366**

Attorney, Agent, or Firm—Sughrue, Mion, Zinn, Macpeak & Seas

[22] Filed: **May 7, 1992**

CLAIM

[30] Foreign Application Priority Data

The ornamental design for a magnetic tape storage unit for an electronic computer, as shown and described.

Nov. 7, 1991 [JP] Japan 3-33456

[52] U.S. Cl. **D14/108**

[58] Field of Search 312/208.1, 223.2, 223.3, 312/194; 360/99.12; 361/390-395; D14/100, 102, 107, 108, 109; D13/162, 184, 199

DESCRIPTION

[56] References Cited

FIG. 1 is a front, top and right side perspective view of a magnetic tape storage unit for an electronic computer showing our new design;

U.S. PATENT DOCUMENTS

FIG. 2 is a front elevational view thereof;

D. 295,976 5/1988 Aremka et al. .... D14/109 X

FIG. 3 is a rear elevational view thereof;
